(57) **CLAIM**

The ornamental design for a hydration pad for pollinators, as shown and described.

DESCRIPTION

FIG. 1 is a front perspective view of the hydration pad for pollinators showing my new design.

FIG. 2 is a front elevation view thereof.

FIG. 3 is a back elevation view thereof.

FIG. 4 is a left elevation view thereof.

FIG. 5 is a right elevation view thereof.

FIG. 6 is a top plan view thereof.

FIG. 7 is a bottom plan view thereof; and,

FIG. 8 is a perspective view thereof, shown in use.

The broken lines in FIG. 8 showing the hydration pad for pollinators in use illustrate environment that forms no part of the claim.

1 Claim, 4 Drawing Sheets
